UNITED STATES PATENT OFFICE.

FRANK S. HOLTZ, OF BERKELEY, CALIFORNIA.

RADIATOR CAP.

Application filed October 27, 1925. Serial No. 65,214.

To all whom it may concern:

Be it known that I, FRANK S. HOLTZ, a citizen of the United States, and a resident of Berkeley, in the county of Alameda and State of California, have invented a new and useful Radiator Cap, of which the following is a specification.

This invention relates to closures for the ends of pipes, and is particularly adapted 10 as a closure or cap for automobile radiators.

An object of the invention is the provision of a closure or cap which can be readily expanded into a funnel, thus functioning as two different devices.

15 With the foregoing object in view, together with such other objects and advantages as may subsequently appear, this invention resides in the construction and arrangement herein described and claimed 20 and illustrated in the accompanying drawings in which:—

Figure 1 is a perspective view of an embodiment of my invention, showing same in closed position.

25 Figure 2 is an enlarged vertical section of Figure 1.

Figure 3 is a cross section taken on the line 3—3 of Figure 2.

30 Figure 4 is a perspective view of a screw employed in the device shown in the drawings, and

Figure 5 is a plan view of my device showing the same in open or funnel formation.

35 Referring to the drawings for more detailed description thereof, the numeral 7 indicates a tubular member circular at its lower portion for flaring outwardly in its upper portion and terminating in four 40 straight upper end portions 8, 9, 10 and 11, which are at right angles to each other.

These upper end portions are circularly bent to form tubes through which are respectively passed pins 12, 13, 14, and 15. 45 The ends of the straight tubular members 8, 9, 10 and 11 are cut away at their ends so that the ends of the pins 12 to 15 inclusive project therefrom. Plates 17, 18, 19 and 20 are respectively hingedly secured 50 to the upper tubular end portions 8, 9, 10 and 11 by having lower end portions thereof bent around the end portions of the pins 12, 13, 14 and 15 which protrude from the tubular portions 8, 9, 10 and 11.

55 These plates are adapted to be swung inwardly to the position shown in Figure 1,

so that they form a four-sided truncated pyramid. The adjacent sides of the adjacent plates, being bevelled, contact with each other so that close joints are made. 60 The lower end portions of the plates 17, 18, 19 and 20, which are opposite the tubular portions 8, 9, 10 and 11, are arcuately formed in order to accurately contact and make a tight joint with their respective opposing 65 tubular portions when the plates are in close pyramidal formation.

The plates are also capable, by means of their hinged connection, of being swung outwardly into the position shown in Figure 70 5. Extensible means are provided to fill in the gaps which exist between the plates when the latter are in the open position shown in Figure 5, and such extensible means may be hinges 25, 26, 27 and 28. 75 These hinges are adapted to fold inwardly when the plates 17 to 20 inclusive are in closed formation, the hinges then assuming the positions shown in Figures 2 and 3. These hinges 25 to 28 inclusive respectively 80 comprise leaves 29—30 hinged at 31, 32—33 hinged at 34, 35—36 hinged at 37, 38—39 hinged at 40.

The leaves 29, 30, 32, 33, 35, 36, 38 and 39 are respectively hinged at similar sides 85 thereof by means of hinges 42, 43, 44, 45, 46, 47, 48 and 49, which are respectively secured to the inner sides and near the side edges of the plates 17, 18, 19, 19, 20, 20, 17. 90

It will thus be seen that the hinges limit the outward movement of the plates. It will also be seen that the leaves of the hinges being alike and hinged together at the corners of the square, formed by the 95 top of the tubular member 7, fill the gaps which exist between the sides of the plates when the latter are in their open formation, and that thus the plates and leaves of the hinges form a funnel which is useful in 100 filling an automobile radiator.

The tops of the plates 17 to 20 inclusive have extensions of reduced width which extensions are respectively numbered 52, 53, 54 and 55. These extensions are bent at an 105 angle to the plates so that when the latter are closed into a pyramidal formation the extensions are vertical.

The cover is provided to close the top of the truncated pyramid, such cover being 110 designated by the numeral 57, which has a recess 58 in its bottom. This recess encloses

the extensions 52 to 55 inclusive and holds the plates 17 to 20 inclusive, together. The cover 57 is provided with a hinge 59, one leaf of which is secured to the plate 17, 5 while the other leaf is secured to the top of the recess by means of screws 60.

In order to hold the cover securely around the extensions of the plates a screw 61, shown in Figure 4, passes through that side of 10 the cover 57 which is opposite the pintle of the hinge 59, into the recess 58 and threadedly engages the cover. The screw also passes through an aperture 62 in the extension 54 when the plates are in closed formation, thus securely holding the cover in an encircling position on the extensions of the plates, since the screw is provided with a 15 head 63 which abuts against the outer surface of the cover 57. The screw 61 is also provided with an end member 64, so that the screw cannot be lost from the cover.

When it is desired to open the device in order to form a funnel, the screw 61 is turned until the end member 64 is withdrawn from the extension 54. The cover 57 is then pushed upwardly and backwardly; this motion of the cover is effective in opening the plates and the hinges into the shape of a funnel.

30 The device described and shown may be secured to a tube existing on a radiator or to the end of any other tube or pipe by a set screw 65, passing transversely through one side of the tubular member 7. The set screw 35 65 has a pointed end 66 which may engage the tube or pipe to which the device of my invention is to be secured.

I claim:—

1. In a device of the character described, 40 a tubular member, plates hinged to said tubular member at their bases and adapted to meet at their adjacent sides, and extensible means hingedly connected to the adjacent plates.

45 2. In a device of the character described, a tubular member, plates hinged to said tubular member at their bases and adapted to meet at their adjacent sides, and extensible means hingedly connected to the adjacent 50 plates and a cover secured to one of said plates.

3. In a device of the character described, 55 a tubular member, plates hinged to said tubular member at their bases and adapted to meet at their adjacent sides, and extensible means highly connected to the adjacent plates and a cover secured to one of said plates and adapted to hold said plates together.

60 4. In a device of the character described, 65 a tubular member, plates hinged to said tubular member at their bases and adapted to meet at their adjacent sides, and extensible means hingedly connected to the adjacent plates and a cover secured to one of said

plates and fitting over the upper end portions of said plates.

5. In a device of the character described, 70 a tubular member, plates hinged to said tubular member at their bases and adapted to meet at their adjacent sides, and extensible means hingedly connected to the adjacent plates and a cover hingedly secured to one of said plates.

6. In a device of the character described, 75 a tubular member, plates hinged to said tubular member at their bases and adapted to meet at their adjacent sides, and extensible means hingedly connected to the adjacent 80 plates and a cover hingedly secured to one of said plates and fitting over the upper end portions of said plates.

7. In a device of the character described, 85 a tubular member, plates hinged to said tubular member at their bases and adapted to meet at their adjacent sides, and inwardly 90 folding hinges connected to the adjacent plates.

8. In a device of the character described, 95 a tubular member, plates hinged to said tubular member at their bases and adapted to meet at their adjacent sides, and inwardly 100 folding hinges connected to the adjacent plates and a cover hingedly secured to one of said plates.

9. In a device of the character described, 105 a tubular member, plates hinged to said tubular member at their bases and adapted to meet at their adjacent sides, and inwardly 110 folding hinges connected to the adjacent plates and a cover hingedly secured to one of said plates and fitting over the upper end portions of said plates.

10. In a device of the character described, 115 a tubular member, plates hinged to said tubular member at their bases and adapted to meet at their adjacent sides, and extensible means hingedly connected to the adjacent plates and a cover secured to one of said plates and means for releasably fastening 120 said cover to another of said plates.

11. In a device of the character described, 115 a tubular member, plates hinged to said tubular member at their bases and adapted to meet at their adjacent sides, and inwardly 120 folding hinges connected to the adjacent plates and a cover hingedly secured to one of said plates and means for releasably fastening 125 said cover to another of said plates.

12. In a device of the character described, 130 a tubular member, plates hinged to said tubular member at their bases and adapted to meet at their adjacent sides, and inwardly folding hinges connected to the adjacent plates and a cover hingedly secured to one of said plates and fitting over the upper end portions of said plates and means for releasably fastening said cover to another of said plates.

13. In a device of the character described,

a tubular member, plates hinged to said tubular member at their bases and adapted to meet at their adjacent sides, and extensible means hingedly connected to the adjacent plates and a cover secured to one of said plates, said plates and cover forming a truncated pyramid.

14. In a device of the character described, a tubular member, plates hinged to said tu-

bular member at their bases and adapted to 10 meet at their adjacent sides, and inwardly folding hinges connected to the adjacent plates and a cover hingedly secured to one of said plates and fitting over the upper end 15 portions of said plates, said plates and cover forming a truncated pyramid.

FRANK S. HOLTZ.
